(57) **CLAIM**

The ornamental design for the soldering station, as shown and described.

DESCRIPTION

FIG. 1 is a perspective view of a soldering station in accordance with an embodiment of the present invention; FIG. 2 is a front view of the soldering station of FIG. 1; FIG. 3 is a rear view of the soldering station of FIG. 1; FIG. 4 is a right side view of the soldering station of FIG. 1;

FIG. 5 is a left side view of the soldering station of FIG. 1; FIG. 6 is a top view of the soldering station of FIG. 1; and, FIG. 7 is a bottom view of the soldering station of FIG. 1. The broken lines of the soldering station in FIGS. 1-7 are illustrative of portions of the soldering station that form no part of the claimed design.
